UNITED STATES PATENT OFFICE.

AUGUST J. FONDEVILLE, OF WEST HOBOKEN, NEW JERSEY.

DESIGN FOR A DECORATIVE PLATE.

No. 39,198.

Specification for Design.

Patented March 17, 1908.

Application filed January 22, 1908. Serial No. 412,218. Term of patent 7 years.

To all whom it may concern:

Be it known that I, AUGUST J. FONDEVILLE, a citizen of the United States, residing at West Hoboken, in the county of Hudson and State of New Jersey, have invented a new, original, and ornamental Design for a Decorative Plate, of which the following is a specification, reference being had to the accompanying drawing, forming a part thereof, and which presents a face view of a decorative plate bearing and incorporating my design.

I claim:

The ornamental design for a decorative plate, as shown.
